Primary Examiner—Philip S. Hyder(74) *Attorney, Agent, or Firm*—Cislo & Thomas LLP(57) **CLAIM**

What is claimed is the ornamental design for an abdominal exercise device, as shown in the drawings herein.

DESCRIPTION

FIG. 1. Is a perspective view of my abdominal exercise device;

FIG. 2 is a right side view thereof, wherein the left side view is a mirror image thereof;

FIG. 3 is a front elevation view thereof;

FIG. 4 is a rear elevation view thereof;

FIG. 5. Is a top view thereof; and,

FIG. 6. Is a bottom view thereof.

The broken line portions of the disclosure are for illustrative purposes only and form no part of the claimed design.
